UNITED STATES PATENT OFFICE

2,231,600

ELECTRIC FUSE

Sidney R. Smith, Jr., Pittsfield, Mass., assignor to
General Electric Company, a corporation of
New York

Application January 14, 1939, Serial No. 250,993

4 Claims. (CL 200—117)

The present invention relates to electric fuses and more particularly to so-called "secondary" fuses which are suitable for such purposes as protection of transformers from secondary faults, 5 isolation of service-entrance faults, and banking of transformer secondaries.

The invention has for a principal object the provision of an improved and simplified form of secondary fuse which requires no separate insulating support and is adapted for outdoor installations, such as on overhead distribution lines in conjunction with strain insulators, which has low initial cost and is easy to install and refuse; and which functions upon fuse operation to give 15 a readily observable indication of the operated condition.

A more specific object of the invention is the provision of simple and low cost means for suspension mounting of a common form of expulsion 20 fuse holder directly on conductors of an overhead electric line.

Other objects and the details of that which I consider to be novel and my invention will become apparent from the following description 25 and the claims appended thereto, taken in conjunction with the accompanying drawing in which Fig. 1 shows a fuse device constructed in accordance with the present invention and an exemplary method of installing the fuse device 30 on an electric line, while Fig. 2 is a detail perspective view of certain of the elements of the device of Fig. 1.

It is contemplated that different forms of fuse 35 holders may be employed in the construction of a fuse device in accordance with the present invention, but in the preferred embodiment illustrated there is employed a common form of fuse holder of simple and inexpensive design, readily available on the market, and having already 40 widely accepted usage in other types of fuse cut-outs. This is a particularly advantageous feature of my invention, since it makes possible reduction in variety and number of parts carried in stock for protection and line maintenance purposes, with resultant substantial savings in expense to power companies. Such a fuse holder, 45 as illustrated, comprises an expulsion tube 10, of fibrous or other suitable insulation material, one end of which is closed by a metallic terminal cap 11 screw-threaded thereon and the other end of which tube is open for expulsion of gases therefrom. The fuse holder is adapted to be fused with common forms of cable type fuse links having the desired current interrupting ratings. 50 One end of such fuse link, installed in tube 10,

is electrically connected with terminal cap 11 in a manner well known in the art, while the other end, or flexible cable extension, indicated at 12, projects from the open end of the tube for connection purposes. 5

In the exemplary installation illustrated, which may be at a line sectionalizing point, the fuse device of the present invention is employed in conjunction with a common form of strain insulator, designated 13, which serves to join mechanically in a well known manner, two line conductors 14 and 15. For suspension mounting of the fuse holder on the line conductors, I have provided a pair of electrically conductive articulated mounts. One of these mounts includes a 15 metallic strap 16, secured to fuse tube 10 adjacent the open end of the tube, and a relatively stiff metallic connector or hanger element 17 pivotally joined to strap 16 by means of a bolt 18. Hingedly mounted on element 17, by means 20 of lugs 20, is a flanged clamping plate 21 with a screw-threaded stud 22 and a wing-nut 23 for clamping attachment to a bared portion of a supporting conductor, such as line conductor 15. The other articulated mount includes a metallic 25 strap 26, secured to terminal cap 11, and a relatively stiff metallic connector element 26 pivotally joined to strap 26 by means of a bolt 27. Hanger element 26, similarly to element 17, has a clamping plate with a screw-threaded stud 22 30 and a wing-nut 23 for clamping attachment to a bared portion of a second supporting conductor, such as line conductor 14. As will be evident from the drawing, the right-hand conductive 35 mount, including element 17, is considerably longer than the left-hand mount, including element 26. This serves the important purpose of supporting fuse tube 10 tilted at an angle to the horizontal with the open end of the tube lowermost so that water will not collect in the tube 40 to cause deterioration and possible failure of the fuse link therein. The articulated joints between the elements of the conductive mounts permit adjustment of the positional relationship between the conductor clamps, including plates 21, of the 45 two mounts, and thereby provide for flexibility in mounting of the fuse device so that the device may be accommodated to various sizes of strain insulators and spacings of supporting conductors. 50

The connector element 17 of the right-hand mount has a thumb-screw terminal clamp, indicated at 30, for attachment of fuse link extension 12 thereto. Element 17 also carries a resilient flipper arm 31, one end of which is af- 55 fixed to element 17 by means of a slot 32 and a

pin 33, as best shown in Fig. 2, while the free end of the arm has a hook 34 arranged to engage fuse link cable extension 12. This flipper arm normally tensions the fuse link in fuse tube 10, 5 and upon fuse operation, serves the dual purpose of retracting the cable extension from the fuse tube to lengthen the arc and of providing a readily observable indication of fuse operation, as shown in Fig. 2.

10 For refusing, it is necessary only to detach the clamp of the left-hand mount from conductor 14 and to unscrew cap 11, replace the blown fuse link in the fuse tube with a new fuse link, connect the cable extension of the new fuse link 15 with terminal clamp 30, engage hook 34 with the cable extension, and then re-attach the left-hand mount to conductor 14. The construction and method of mounting of the fuse device insures safety in refusing since a fuse link cannot 20 be inserted in the fuse tube unless at least one of the conductive mounts is detached from its supporting conductor.

From the foregoing it will be seen that I have provided a simple and inexpensive fuse device 25 which requires a minimum of special parts, is easy and safe to install and refuse, and which upon fuse operation gives a readily observable indication while facilitating the circuit interrupting process by drawing out the arc within the 30 fuse tube. Thus my improved fuse device is particularly advantageous for applications where it is desired to provide reliable fused protection at minimum cost. It is contemplated that there will suggest themselves to those skilled in the 35 art modifications of certain details of the illustrated fuse device, such as to adapt the device for various installation conditions encountered. Also, the invention is not limited to the particular forms of fuse link flipper arm and line conductor engaging clamps illustrated in the drawing. Hence it is intended that such modifications as do not depart from the true spirit of the invention shall come within the scope of the appended claims.

40 What I claim as new and desire to secure by Letters Patent of the United States is:

1. A line suspension fuse comprising an insulating fuse tube closed at one end by a removable metallic terminal cap and open at the other 50 end, a conductive mount clamped on said terminal cap, a second conductive mount clamped on said tube adjacent the open end thereof, said mounts having clamps for attachment thereof respectively to electric line conductors for suspension mounting of said tube directly on such conductors, and a terminal clamp on said second mount for securing thereto one end of a fuse link extending out of the open end of said tube.

2. A line suspension fuse adapted to be supported by and electrically to connect two line conductors which are mechanically joined by a strain insulator or the like; said fuse comprising

a fuse holder including an insulating fuse tube having at least one end open, a first conductive mount secured to said holder adjacent said one end of said tube and having a terminal clamp for securing thereto one end of a fuse link extending 5 out of said one end of the tube, a second conductive mount secured to said holder adjacent the other end of the tube, and means to effect electric connection between said second mount and fuse link in the tube, said mounts having 10 clamping means for clamping attachment thereof respectively to conductors for supporting the fuse holder, and at least one of said mounts including a plurality of relatively stiff elements 15 articulated for relative movement so as to provide for variation of the positional relationship between the said conductor clamping means of the two mounts.

3. A line suspension fuse comprising a fuse holder including a fuse tube open at one end and closed at the other end and having a fuse terminal adjacent said closed end, a conductive mount secured to said holder in conductive relation to said terminal, a second conductive mount secured to the holder adjacent the open end of 25 said tube and having a terminal clamp for one end of a fuse link extending from the open end of the tube, said mounts having clamping means for clamping attachment thereof respectively to conductors for supporting said holder and each 30 of the mounts including at least two relatively stiff elements articulated for relative movement so as to provide for adjustment of the positional relationship between the said conductor clamping means of the two mounts, said second mount 35 being substantially longer than said first mount, and a fuse link tensioning and retracting spring device mounted on said second mount for engagement with a portion of a fuse link extending from the open end of the tube, said device having 40 a part movable to a readily observable indicating position upon fuse operation.

4. In a fuse device for suspension mounting directly on the conductors of an electric line, an insulating tubular fuse holder open at one end and having fuse terminal means adjacent the other end, a conductive mount secured on said holder in conductive relation to said terminal means, a second conductive mount secured on said holder adjacent the open end thereof, each 45 of said mounts including a metallic hanger pivotally attached at one end to a metallic strap which is bent so as to extend around said holder and which strap is quick detachably secured to the holder, the other end of each of said hangers 50 having clamping means for attachment to an electric line conductor, and a terminal clamp on said second mount for securing thereto one end of a fuse link extending out of said open end of 55 said holder.

SIDNEY R. SMITH, JR.
